AUTOMATIC CALCULATOR

Walter J. Pasinski, Detroit, Mich., assignor to
Burroughs Adding Machine Company, Detroit,
Mich., a corporation of Michigan

Original application July 2, 1928, Serial No.
289,865. Divided and this application August
22, 1930, Serial No. 477,012

28 Claims. (Cl. 235—144)

This invention relates to a clearing mechanism for calculating machines, the present application being a division of co-pending application Serial No. 289,865, filed July 2, 1928.

5 The general object of the invention is to provide an improved cancelling or clearing mechanism in a machine of the class described which will operate automatically upon the depression of a key.

10 Other and more particular objects will herein-after appear.

An embodiment of the invention is shown in the accompanying drawings in which:

15 Figure 1 is a plan view of a calculating machine with the cancelling mechanism applied thereto.

Fig. 2 is a side elevation and cross-section of said machine showing particularly the cancelling mechanism.

20 Fig. 3 is a detail view illustrating the key interlocking construction, the parts being shown in normal condition.

Fig. 4 is a side elevation of the cancelling mechanism with the parts in operated position.

25 Fig. 5 is another detail view of the key interlocking mechanism showing the parts in locking position.

Fig. 6 is a detail side elevation of a portion of the cancelling mechanism shown in Fig. 4.

30 Figs. 7, 8, and 9 are sections of a portion of the cancelling mechanism showing the parts in different positions, the sections being taken on the line 7—7 of Fig. 4.

Fig. 10 is a partial side elevation and section 35 showing the forward portion of the mechanism of the present invention and certain portions of the cancelling mechanism directly associated with the register.

40 The cancelling mechanism is shown applied to an automatic calculator in which calculations take place in each order immediately upon depression of a key in that order, the machine being motor operated and entirely automatic.

An understanding of the details of the calculator is not necessary for an understanding of the cancelling mechanism and hence the calculator will be described only very briefly. In describing it and in describing the cancelling mechanism the same reference numbers will be used, in so far as possible, as were used in the parent application.

45 The calculator has a plurality of depressible amount keys 10, any one of which, when depressed, closes a switch 57 that starts an electric motor 40 which, when it operates, rotates a main

drive shaft 33 in a counterclockwise direction. Depression of any one of the amount keys in a given bank also acts to connect the differential mechanisms for that bank to a ratchet wheel 47 so that when the motor is operated the differential mechanism is likewise operated. After the differential mechanism has been moved to a position where it is arrested by the depressed amount key said differential mechanism is automatically disconnected from said ratchet wheel and the 10 motor is stopped. The movements of the differential mechanism are imparted to a register 25 at the forward end of the machine and it is this register that must be cleared after a series of calculations. 15

Cancelling mechanism

The cancelling mechanism is entirely automatic and it is set into operation by simply depressing a clearance key 120 illustrated in Fig. 1. 20

The portion of the cancelling mechanism that operates on the register is located at the forward part of the machine and is best shown in Fig. 10. This portion of the mechanism is controlled by an arm 121 which is given a forward and return 25 stroke of movement in clearing as will be described later. This movement of arm 121 first rocks a shaft 122 counterclockwise and then returns it clockwise to its original position. Fixed to the shaft 122 is an arm 200 having a stud 201 30 adapted to engage a cam surface 202 on a U-shaped member having two arms 203 and 204. This member is pivoted at 205 and urged clockwise by a spring 206. The upper end of the arm 203 engages a stud on an arm 207 fixed to a shaft 35 208 that extends across the machine. This shaft has a series of dogs 209 on it, there being one dog for each column or bank of the machine. These dogs are adapted to engage driving pawls 210 of which there is one for each bank. During operation of the machine the driving pawls drive the ratchet wheels 211 in a counterclockwise direction and these wheels, in turn, drive the register pinions 25. 40

When the arm 121 is rocked counterclockwise 45 the U-shaped member 203—204 is swung in the same direction and the arm 207 is moved clockwise to thereby rock the shaft 208 clockwise. This causes the dogs 209 to engage the pawls 210 to release them from the ratchet wheels 211 50 so that the register pinions are free for return to their zero positions under the influence of a spring and cam action such as described in Horton Patent No. 1,326,504, to which reference is made for details. The mechanism directly 55

associated with the register and above described has been used for a number of years on the Burroughs calculators and the present invention does not concern its details.

- 5 Referring to Fig. 2, the arm 121 is rocked by means of the link 123 having a downwardly extending projection 124 to which one end of a spring 125 is connected. The other end of this spring is connected to a projection 126 on a link 10 127 having a pin and slot connection with the arm 121. When the arm 127 is moved forwardly it moves the link 123 forward through the spring 125 and thereby moves the arm 121 forward, the connection being a yielding one so that, in the 15 event the cancelling mechanism becomes blocked or is sluggish for some reason, the spring will yield and the parts will not be damaged. The link 127 is moved forward by being connected to the motor drive, the motor being started and 20 such connection being effected by depression of the key 120.

The key 120 has a stem 130 slidably mounted on studs 131 on the side frame 132 of the machine. The lower end of the stem has a lateral extension 133 to which is pivoted a pawl 134. This pawl is urged clockwise by a spring 135 into engagement with the edge of a lug 136 of a lateral projection 137 on an inner slide plate 138 mounted on studs 139. The pawl 134 has 30 a shoulder 140 for engaging the lug 136. When the key 120 is depressed the shoulder 140 moves into engagement with lug 136 to move the slide 138 downwardly whereupon a pivoted latch 141 snaps into position to hold the slide depressed, 35 such latching action normally taking place because the end of pawl 141 passes over the lug 136 as shown in Fig. 4. If the key 120 is only partially depressed the latching action also takes place, but in this case the lug 136 is held down 40 by the engagement of a shoulder 142 (Fig. 2) of the latch 141 over lug 136. The spring 135 which urges the pawl 134 clockwise is also connected to the latch 141 to urge it counterclockwise, one spring serving for both parts. The 45 slide 138 is moved down against the tension of a spring 143 connected at one end to a stud 144 (Figs. 7 and 8) on the slide and at its other end to a stud on the side plate 132.

The slide 138 has a rearwardly projecting cam hook 145 having a beveled surface 146 adapted to engage a stud 147 on an arm 148 pivoted at 149 and connected to the bail 58 that controls the starting of the motor, the bail being urged clockwise by the spring 59. When the key 120 is depressed and the slide 138 is moved downwardly, the cam hook 145, acting on the stud 147, cams the arm 148 counterclockwise sufficiently to move the bail 58 to effect a starting of the motor. In this manner the motor is started when the 60 cancelling key 120 is depressed.

The cancelling mechanism is connected to the motor drive by means of a second slide 150 also mounted on the studs 139. The first slide 138 has a projection 151 to which one end of a spring 65 152 is connected, the other end of said spring being connected to a projection 153 on slide 150. When slide 138 is moved down by depression of the cancellation key 120, it pulls the slide 150 down with it through the yielding connection 70 provided by spring 152. The slide 150 has a pin 154 projecting from it through a slot 155 in slide 138 and this pin projects over the cancelling link 127 as shown in Fig. 8. Accordingly, upon depression of the key 120, the link 127 is swung 75 downward against the tension of a spring 156

which tends to hold it up and rearward, the position of the slides when the key is depressed being shown in Fig. 9. The rear end of the link 127 has a notch 160 in it adapted to engage over a stud 161 on a pivoted arm 162. The arm 162 is urged clockwise by a spring 163 and it has an extension 164 carrying a stud 165 bearing on the edge of a two-faced cam 166 fixed to the shaft 33 which is rotated by the motor. When the key 120 is depressed the link 127 is 1 thus connected to the arm 162 and, since the motor is started by depression of the key 120 as previously explained, the cam 166 rocks the lever 162 counterclockwise which moves the link 127 forward to operate the clearing mechanism. 1

As the link 123 moves forward with the link 127, a downward projection 170 on it engages a lateral lug 171 on the pawl 134, thereby moving the pawl counterclockwise. The edge of the pawl engages against a lateral lug 172 on the latch 141. The result is that the forward movement of the link 123 disables both the pawl 134 and the latch 141 by moving them out of the path of the lug 136, thereby freeing the slide 138 to permit the spring 143 to return the slide to normal. This 2 frees the arm 148 connected with the motor starting bail 58 and stops the motor. As the slide 138 moves upwardly the bottom edge of its slot 155 contacts the pin 154 and carries it upwardly thereby freeing the link 127. The high surface 3 of the cam 166 having passed the stud 165, the arm 162 is rocked clockwise back to normal by spring 163. The link 127 is moved back by its spring 156 which, near the end of the return stroke of the link, lifts the latter upwardly to 3 disconnect it from the stud 161. The parts are thus returned to normal and it is to be noted that the zeroizing mechanism is disconnected and the motor stopped independently of the length of time that the cancellation key 120 is held de- 4 pressed. The actuating operation, or forward movement, of the link 127 disconnects the pawl 134 from the lug 136 of the slide 138 thereby 41 disabling the control of slide 138 by key 120. The slide 138 returns to normal under the influence 41 of its spring and releases link 127 to enable it to be pulled to disconnected position by spring 156. Upward movement of slide 138 also releases the motor starting means including bail 58 so that the latter may move to position to stop the motor. 50 As long as the key 120 is held depressed, the pawl 134 cannot be reconnected with the slide 138 and hence a second operation of the zeroizing mechanism or a continuous operation of the motor cannot take place. It is necessary to release 55 the cancellation key 120 and to give it a second depression in order to get a second operation of the zeroizing mechanism.

The cam 166 is constructed so that its high 60 surfaces will act on the stud 165 twice during one revolution of the shaft 33. The purpose of this is to secure a quick action so as to waste as little time in cancelling operations as possible. In the event the notch 160 in the link 127 is not 65 immediately over the stud 161 when the key 120 is depressed, the parts will not be immediately connected together but they will be connected very quickly. Depression of the key starts the motor which rotates the cam 166 and gives the 70 arm 162 a stroke of movement. As the key is depressed the slide 138 moves downwardly and puts a tension on spring 152 to urge the slide 150 downwardly to cause its pin 154 to engage the top of the link 127 thereby urging the rear 75

end of the latter downwardly. If the slot 160 and the stud 161 are in alignment, the link 127 is immediately connected to arm 162. If they are not in alignment the slides 138 and 150 assume the position shown in Fig. 8. The slide 138 moves down but the slide 150 is retained upward by link 127. The rear end of link 127 rides on the stud 161 until the arm 162 is returned to its rearward position whereupon the notch 160 snaps over the stud 161 and the parts are connected together. The motor continues to operate because the connections for operating it are not disconnected until the link 127 is given a forward stroke of movement. Accordingly, after the parts are connected together as above described, the link 127 is given a forward stroke to effect cancelling operations whereupon the motor is automatically stopped.

In the event the cancelling mechanism should be blocked in any way, the link 127 moves forward without moving the link 123 forward, the spring 125 stretching and the parts assuming the position illustrated in Fig. 6. When this occurs a latch 180, urged counterclockwise by a spring 181, latches behind a shoulder 182 on the link 127 and holds the link in its forward position. Since the link 123 is not moved forward under these conditions the latch 141 remains in position over the lug 136 and the motor continues to operate to repeatedly oscillate the link 127, the link being returned each time by the spring 125. This oscillation of the link 127 and the continued running of the motor indicates to the operator that something is wrong. Besides which the keys will be found locked, as will be later explained. The link 127 can oscillate without being disconnected from the pin 161 on arm 162 owing to the fact that the notch 160 allows for some play of the parts and owing further to the fact that the shoulder 182 is located so that when the link 127 is in its farthest forward position, the shoulder is slightly forward of the latch 180. The link 127 may thus have a short oscillatory movement without being disconnected from arm 162 which latter does not return to its fully returned position, but returns to such a position that the cam 166 gives the arm a short oscillatory movement. When the difficulty in the cancelling mechanism has been removed, the link 123 will snap forward under the tension of its spring 125, whereupon a raised projection 183 on the link 123 cams the latch 180 upward to release the link 127 to permit the latter to be moved back to normal under the influence of its spring 156. During normal operations, when there is no difficulty with the cancelling mechanism the raised projection 183 moves forward at the same time that the two links 123 and 127 are moved forward and it disables the latch 180 at the end of the forward stroke to prevent said latch from becoming effective to hold the link 127 forward.

Means for locking amount keys while cancellation takes place

Whenever the cancellation key 120 is depressed to effect a cancellation, all of the amount keys are locked against depression by a mechanism as follows.

The slide 150 has a lateral projection carrying a stud 190 operating in a cam slot 191 in one arm 192 of a pivoted bell crank lever whose other arm 193 is provided with a cam slot 194 engaging a stud 195 on an arm connected to a pivoted shaft 196. This shaft extends across the

rear of the machine and it has a series of slots 197 forming a series of semi-circular shaft sections which are aligned with the rearmost of the key interlocking pendants 198 illustrated in Figs. 3 and 5. These pendants are of the familiar type used in the Burroughs calculator, the same being illustrated and described in Horton Patent No. 1,243,839. There is one of these pendants between each two keys and one to the rear of the "9" key and their lower ends are spaced so that there is just enough clearance to permit one key to be depressed at a time. Whenever a key is depressed the pendants are moved together so closely that there is no space to depress a second key. 15

When the cancellation key 120 is depressed and the slide 150 is moved downwardly the bell crank lever 192—193 is moved clockwise which rocks the shaft 196 clockwise from its Fig. 3 to its Fig. 5 position. The edges of the slots 197 swing 20 the rear pendants 198 forward and move all of them in each of the rows so close together that none of the keys in any of the banks can be depressed. In this manner, as soon as the cancellation key 120 is depressed, all of the amount 25 keys are locked against depression. Also, when one of the amount keys is depressed, the shaft 196 is blocked against turning which prevents depression of the cancelling key 120 when an amount key is depressed. 30

When the cancellation key 120 is released and the slide 138 is moved upwardly under the influence of its spring 143, said slide engages the pin 154 on the slide 150 and moves the latter upwardly which cams the bell crank lever 35 192—193 counterclockwise to swing the shaft 196 counterclockwise thereby releasing the interlocking pendants 198 and freeing the amount keys.

I claim:

1. A calculating machine having a register, a zeroizing mechanism therefor, a normally inactive motor for driving said zeroizing mechanism, a slidable means urged toward a normal position, a depressible key for moving said slidable means away from its normal position, a latch 45 for holding said slidable means in the position to which it is moved, a linkage mechanism for connecting said motor to said zeroizing mechanism, connections operated by said slidable means as it is moved to start said motor, said slidable means 50 also having a portion acting to move said linkage mechanism to position for connection to said motor, and means carried by said linkage mechanism operating to release said latch during the movement of said linkage mechanism to thereby release said slidable means to permit it to return to normal, said slidable means, in returning to normal, acting to release said motor starting mechanism to stop said motor and to release said linkage mechanism to permit it to be disconnected from said motor. 55

2. A calculating machine having a register, a zeroizing mechanism therefor, a motor for driving said zeroizing mechanism, a linkage mechanism between said motor and zeroizing mechanism, said linkage mechanism including one link connected to said zeroizing mechanism and a second link adapted to be driven by said motor, a yielding connection between said links, a slidable means urged toward a normal position, a 70 depressible key having a pivoted pawl releasably connected to said slidable means so that, upon depression of said key, said slidable means will be moved away from normal, connections operated by said slidable means as it moves away 75.

- from normal causing said motor to drive the link connected to said motor, said first link having a portion acting when it is moved by said second link to disable said pawl.
5. A clearing mechanism for calculating machines of the class described comprising, in combination with a machine having a register and a zeroizing mechanism therefor, a power driving means, normally disconnected operating connections between said power driving means and said zeroizing mechanism, a manipulative member for conditioning said connections to connect said zeroizing mechanism to said driving means, and means operating automatically as said zeroizing mechanism is operated to disconnect said operating connections irrespective of the position of said manipulative member.
6. A clearing mechanism for calculating machines of the class described comprising, in combination with a machine having a register and a zeroizing mechanism therefor, a power driving means, normally disconnected operating connections between said power drive and said zeroizing mechanism, a manipulative member for conditioning said connections to connect said zeroizing mechanism to said power driving means, and means actuated by said operating connections as the same are moved to complete the operation of said zeroizing mechanism for automatically disconnecting said zeroizing mechanism from said power drive independently of the position of the manipulative member.
7. A clearing mechanism for calculating machines of the class described comprising, in combination with a machine having a register and a zeroizing mechanism therefor, a power driving means, operating connections between said power driving means and said zeroizing mechanism urged to disconnected position, a manipulative member for moving said connections to connected position, a latching means for latching said connections in connected position, and means operating automatically to release said latching means as said operating connections complete their actuating movement in their operation of the zeroizing mechanism.
8. A clearing mechanism for calculating machines of the class described comprising, in combination with a machine having a register and a zeroizing mechanism therefor, a power driving means, a link for connecting said zeroizing mechanism to said power driving means, said link being urged to disconnected position, means conditioned by a manipulative member for moving said link to and holding it in connected position, a latch for holding said means in the position to which it is moved by said manipulative member, and means operated by said link as it completes its actuating movement in operating said zeroizing mechanism for automatically releasing said latch.
9. A clearing mechanism for calculating machines of the class described comprising, in combination with a machine having a register and a zeroizing mechanism therefor, a normally inactive motor, normally disconnected operating connections between said zeroizing mechanism and motor, means conditioned by a manipulative member for automatically starting said motor and connecting said zeroizing mechanism to said motor, and means operating automatically and independently of the position of said manipulative member to stop said motor and disconnect it from said zeroizing mechanism after the latter has been operated.
10. A clearing mechanism for calculating machines of the class described comprising, in combination with a machine having a register and a zeroizing mechanism therefor, a normally inactive motor, normally disconnected operating connections between said zeroizing mechanism and motor, means conditioned by manipulation of a manipulative member for starting said motor and connecting said zeroizing mechanism to said motor, and means operated by said operating connections as the same complete their actuating movement in operating said zeroizing mechanism for automatically stopping said motor and disconnecting said operating connections from said motor independently of the position of said manipulative member.
11. A clearing mechanism for calculating machines of the class described comprising, in combination with a machine having a register and a zeroizing mechanism therefor, a normally inactive motor, operating connections between said zeroizing mechanism and motor urged to disconnected position, motor starting means urged to non-starting position, controlling means conditioned by a manipulative member for moving said operating connections to connected position and said motor starting means to starting position, a latch for holding said controlling means in the position to which it is moved, and means operating automatically after said zeroizing mechanism has been actuated to release said latch to release said controlling means to enable said motor starting means to move to non-starting position and said operating connections to move to disconnected position.
12. A clearing mechanism for calculating machines of the class described comprising, in combination with a machine having a register and a zeroizing mechanism therefor, a normally inactive motor, operating connections between said zeroizing mechanism and motor urged to disconnected position, motor starting means urged to non-starting position, controlling means conditioned by depression of a clearance key for moving said operating connections to connected position and said motor starting means to starting position, a latch for holding said controlling means in the position to which it is moved by said clearance key, and means actuated by said operating connections as the latter complete their actuating movement for releasing said latch.
13. A clearing mechanism for calculating machines of the class described comprising, in combination with a machine having a register and a zeroizing mechanism therefor, a power driving means, normally disconnected operating connections between said zeroizing mechanism and power driving means, a clearance key controlling said connections to condition them to connect said zeroizing mechanism to said power drive, and means operating automatically to disable the control of said operating connections by said clearance key until said operating connections have returned to normal after having been moved to actuate said zeroizing mechanism.
14. A clearing mechanism for calculating machines of the class described comprising, in combination with a machine having a register and a zeroizing mechanism therefor, a power driving means, normally disconnected operating connections between said power driving means and said zeroizing mechanism, a manipulative member releasably connected to said connections for conditioning them to connect said zeroizing mechanism to said driving means, and means operated

automatically by said connections as they move to operate said zeroizing mechanism for automatically disconnecting said manipulative member from said operating connections until said operating connections return to normal.

13. A clearing mechanism for calculating machines of the class described comprising, in combination with a machine having a register and a zeroizing mechanism therefor a power driving means, normally disconnected operating connections between said zeroizing mechanism and power driving means, said connections having a forward and a return stroke of movement in operating said zeroizing mechanism, a clearance key for controlling said operating connections to condition them to connect said zeroizing mechanism to said power drive, and means operated by said connections during their forward stroke for automatically disabling the control of said operating connections by said clearance key until said operating connections have completed their return stroke.

14. A clearing mechanism for calculating machines of the class described comprising, in combination with a machine having a register and a zeroizing mechanism therefor, a power driving means, normally disconnected operating connections between said power driving means and said zeroizing mechanism, a manipulative member for controlling said connections to condition them to connect said zeroizing mechanism to said driving means, and means operating automatically as said connections are moved to operate said zeroizing mechanism for automatically disconnecting said zeroizing mechanism from said power drive and automatically disabling the control of said connections by said manipulative member until said connections have returned to normal.

15. A clearing mechanism for calculating machines of the class described comprising, in combination with a machine having a register and a zeroizing mechanism therefor, a normally inactive motor, normally disconnected operating connections between said zeroizing mechanism and motor, controlling means conditioned by a manipulative member for starting said motor and connecting said zeroizing mechanism to said motor, and means operating automatically, after said operating connections have been moved to actuate said zeroizing mechanism, to stop said motor, to automatically disconnect said operating connections from said motor, and to automatically disable the control of said connections by said manipulative member until said connections have returned to normal position.

16. A clearing mechanism for calculating machines of the class described comprising, in combination with a machine having a register and a zeroizing mechanism therefor, a power driving means, normally disconnected operating connections between said zeroizing mechanism and power driving means, said connections being adapted to be given a forward and a return stroke of movement in operating said zeroizing mechanism and having a portion that is movable when said zeroizing mechanism is blocked at the time said connections are moved, a clearance key for conditioning said connections to connect said zeroizing mechanism to said driving means, means operating automatically during the forward stroke of said connections to disable the control of said connections by said clearance key until the return of said connections to normal, and means preventing the return of said connections to normal when said zeroizing mechanism is not

operated during the forward stroke of said operating connections.

17. A clearing mechanism for calculating machines of the class described comprising, in combination with a machine having a register and a zeroizing mechanism therefor, a power driving means, a normally disconnected operating connection between said zeroizing mechanism and power driving means including two links yieldingly connected together, the first of said links being adapted to be connected to said driving means and the second being connected to said zeroizing mechanism, a clearance key for conditioning said operating connections to connect said zeroizing mechanism to said power driving means, means operated automatically by said second link, which is connected to said zeroizing mechanism, for disabling the control of said operating connections by said clearance key when said second link is moved to operate said zeroizing mechanism, a latch operable to hold said first link in its forward position, and means carried by said second link for releasing said latch when said second link moves to a position to operate said zeroizing mechanism.

18. In a machine of the class described, a plurality of depressible amount keys, a register, clearing mechanism for said register, power driving means for said clearing mechanism, driving connections conditioned by depression of a clearance key for connecting said power driving means to said clearing mechanism to move the latter, means conditioned by depression of said clearance key for locking the amount keys against depression, and means operated by said driving connections as said register is cleared for releasing said locking means.

19. In a machine of the class described, a plurality of depressible amount keys, a register, a clearing mechanism for said register, power driving means for said clearing mechanism, driving connections conditioned by depression of a clearance key for connecting said power driving means to said clearing mechanism for a clearing operation, latching means for holding said driving connections in the position to which they are moved by said clearance key, means conditioned by said clearance key at the same time that said driving connections are conditioned for locking said amount keys against depression, said key locking means being held in locking position by said latching means after being moved to locking position, and means for automatically releasing said latching means as said register is cleared.

20. In a machine of the class described, a calculating mechanism, a register, clearing mechanism for said register, power driving means, a member oscillated by said driving means, linkage mechanism connected to said clearing mechanism, said linkage mechanism having a link adapted to be positioned in the path of said oscillating member but being normally held out of the path of said member, and means operable by a manipulative member for moving said link into the path of said oscillating member to thereby cause said power drive to operate said clearing mechanism.

21. In a machine of the class described, a calculating mechanism, a register, clearing mechanism for said register, power driving means, a member oscillated by said driving means, linkage mechanism connected to said clearing mechanism, said linkage mechanism having a link adapted to be positioned in the path of said oscillating member but being normally held out

of the path of said member, means operable by depression of a clearance key for moving said link into the path of said oscillating member to thereby cause said power drive to operate said clearing mechanism, and means automatically releasing said link to permit the same to return to normal after said clearing mechanism has been operated.

22. In a machine of the class described, a calculating mechanism, a register, clearing mechanism for said register, power driving means, a cam rotatable by said power driving means, a pivoted lever carrying a roller adapted to be engaged by said cam, a linkage mechanism connected to said clearing mechanism, said linkage mechanism having a link adapted to be engaged by said pivoted lever but being normally held in a disengaged position, and means operable by a clearance key for moving said link into the path of said pivoted lever.

23. In a machine of the class described, a calculating mechanism, a register, clearing mechanism for said register, power driving means, a cam rotatable by said power driving means, a pivoted lever carrying a roller adapted to be engaged by said cam, a linkage mechanism connected to said clearing mechanism, said linkage mechanism including a link having a shoulder adapted to be engaged by a second roller on said pivoted lever, means normally holding said link out of the path of said second roller, a clearance key having connections operable, upon depression of said key, to move said link so that its shoulder is in the path of said second roller, and means operating automatically as said linkage mechanism is moved to operate the clearing mechanism to cause said link to be returned to its normal position with its shoulder out of the path of said second roller.

24. In a calculating machine of the class described, a plurality of depressible amount keys, a register, clearing mechanism movable to clear said register including portions movable during a clearing movement even though said register is not cleared by said movement, and means locking the amount keys against depression when movement of the clearing mechanism does not clear said register.

25. In a machine of the class described, a plurality of depressible amount keys, a register clearing mechanism for the register, power driving means for said clearing mechanism, driving connections for connecting said power drive to said

clearing mechanism to operate the same, said driving connections including portions movable by said power drive for a clearing movement even though said register is blocked against clearing, and means locking the amount keys against depression when the movement of said driving connections by said power drive does not clear said register.

26. In a machine of the class described, a plurality of depressible keys, a register, a clearing mechanism for said register, a power driving means for said clearing mechanism, driving connections conditioned by depression of a clearance key for connecting said power driving means to said clearing mechanism for a clearing operation, locking means conditioned simultaneously with said driving connections for locking the amount keys against depression, and latching means for holding said driving connections in connected position and said locking means in locked position, said driving connections including portions normally releasing said latching means as the register is cleared but having provisions for permitting operation of the connections without releasing said latching means when said register is blocked against clearing, said locking means preventing said amount keys from being depressed as long as said latching means is not released.

27. A key responsive calculator of the class described having a register, a clearing mechanism for said register adapted to clear said register by a single stroke of operation, a power driving means, a clearance key, and means conditioned by depression of said clearance key for causing said power driving means to automatically give said clearing means a single stroke of operation only irrespective of the length of time that the key is held depressed.

28. A key responsive calculator of the class described having a register, a clearing mechanism for said register adapted to clear said register by a single stroke of operation, a normally inactive motor driving means, a clearance key, and means conditioned by depression of said clearance key for starting said motor, for causing said motor to give said clearing mechanism a single stroke of operation only regardless of how long the clearance key is held depressed, and for then automatically causing said motor to be stopped after said clearing mechanism has been operated.
